BRASSIÈRE

Rose Marie Reid, Boise, Idaho

Application May 27, 1944, Serial No. 537,679

4 Claims. (Cl. 2—42)

My invention relates to a brassière.

A feature of my brassière is that it can be applied or tied in operative position, to fit the bust tightly or loosely as desired, while effectively covering the bust.

Another feature of my invention is that a particular or given size of the brassière can be made to serve a certain range of bust development, the applicability of such given size being limited mostly only by the size of the person, more particularly by the width of the back, (as measured between the arm pits) and the distance between the arm pits and the back of the neck.

Another feature is that it is simple of manufacture, is neat, and is attractive when applied.

Another feature is that it can be applied or tied in two different manners, to suit one's taste or convenience, thereby presenting two slightly different appearances or forms.

Another feature is that it fits well under the arm pits, thereby better covering and encompassing the bust.

In the drawings,

Figure 1 shows the brassière when applied, as seen from the front;

Figure 2 is a rear view of Figure 1;

Figure 3 shows the brassière when tied or applied in a manner different to that shown in Figure 1; and

Figure 4 is a flat or developed view of the brassière of the present invention.

Referring now to the drawings, wherein like numerals of reference indicate corresponding parts in the various figures, 10—10 are two members suitably spaced and shaped to cover the bust, and to provide waist circling straps or ties. The upper edge or end of each member is stitched to a band 11, which forms a neck band. The band is extended beyond its opposite ends into straps 12—13, disposed at an angle to the band 11. The straps 12—13, when fastened as by say a button 15 secured to one strap and a button hole 14 in the other strap, pass under the arm pits and extend across the back, serving to hold or support the upper end of the brassière in operative position. The members are so spaced that they extend partly under the arm pits.

In practice, the member is formed with a curved edge, 16, which for the sake of appearance may be trimmed with fancy edging 17, and the upper edge of the member is slightly full or Shirred to give more fullness over the bust. The members taper off to form ties 18 adapted to circle the

waist and to be tied together at the back to thus hold the brassière well against the bust. If preferred, the straps 12 and 13 may be made into a single continuous, elastic or readily stretchable band, that is, one single continuous elastic member would extend between the opposite ends of the band 11, thus obviating the necessity of a button hole and a button such as shown at 14 and 15, respectively.

10 The band 11 is applied around the neck and over the shoulders and under the arm pits and the straps 12—13 drawn across the back and buttoned together as shown in Figures 1 and 2. Then the ties 18 are drawn around the waist and tied 15 across the back, as shown in Figure 2, or first knotted below the bust as at 19 (see Figure 3), and then tied across the back.

What I claim is:

1. A brassière comprising two spaced bust-covering members having supporting means adapted to engage the back of the neck and shoulders and pass under the arm pits to be fastened across the back, said members including ties adapted to be crossed below the bust and 25 drawn around the waist to be fastened across the back.

2. A brassière comprising a band adapted to engage the back of the neck and shoulders and pass under the arm pits to have its ends detachably secured together across the back, and two spaced bust-covering members suspended from said band adapted to be crossed over the bust and terminating in ties adapted to be drawn around the hips to be tied together across the back.

3. A brassière comprising a pair of spaced bust-covering members adapted to be crossed over the bust and including ties adapted to be drawn over the hips to be tied together around the waist, and a band suspending the upper ends of said bust-covering members adapted to engage the back of the neck and shoulders and pass under the arm pits to be tied together around the back.

4. A brassière comprising a pair of spaced bust covering members adapted to be crossed over the bust and including ties adapted to be drawn over the hips to be tied together around the waist, and a continuous elastic band secured to said bust covering members to support the same, said band being adapted to engage the back of the neck and 45 shoulders and pass under the arm pits and engage the back.

ROSE MARIE REID.
